[57] CLAIM

The ornamental design for the combined condiment dishes and server, as shown and described.

DESCRIPTION

FIG. 1 is a top plan view of combined condiment dishes and server showing my new design;

FIG. 2 is a side elevational view thereof, the undisclosed sides being similar to the side shown;

FIG. 3 is a bottom plan view thereof; and

FIG. 4 is a cross-sectional view taken along line 4—4 in FIG. 1.
